UNITED STATES PATENT OFFICE.

JACOB R. HANN, OF JACKSON, MICHIGAN.

PRESSER-FOOT FOR SEWING-MACHINES.

SPECIFICATION forming part of Letters Patent No. 765,619, dated July 19, 1904.

Application filed September 11, 1903. Serial No. 172,792. (No model.)

To all whom it may concern:

Be it known that I, JACOB R. HANN, a citizen of the United States, residing at Jackson, in the county of Jackson and State of Michigan, have invented certain new and useful Improvements in Presser-Feet for Sewing-Machines, of which the following is a specification.

This invention relates to sewing-machine attachments, and more particularly to the presser-foot, and is designed to prevent skipping of stitches of sewing-machines of ordinary or special construction by providing a foot of novel formation and comprising elements or members which will exert a uniform pressure upon different thicknesses of goods or work comprising two or more layers or folds.

For a full description of the invention and the merits thereof and also to acquire a knowledge of the details of construction of the means for effecting the result reference is to be had to the following description and drawings hereto attached.

While the essential and characteristic features of the invention are susceptible of modification, still the preferred embodiment of the invention is illustrated in the accompanying drawings, in which—

Figure 1 is a perspective view of a multiple or gang presser-foot. Fig. 2 is a section on the line X X of Fig. 1 looking in the direction of the arrows. Fig. 3 is a vertical central longitudinal section on the line Y Y of Fig. 1. Fig. 4 is a section of the complete foot on the line Z Z of Fig. 3. Fig. 5 is a perspective view of the guide and stop-frame.

Corresponding and like parts are referred to in the following description and indicated in all the views of the drawings by the same reference characters.

The presser-foot comprises a head 1, provided with a clamp 2 or analogous means for securing the attachment to the presser-bar of the sewing-machine, the combined guide and stop 3 and the presser members or elements 4, which are pivoted to the head 1, so as to have independent movement, each being forced downward by a spring 5. Any number of presser members or elements 4 may be

provided, according to the style of machine and the character of work to be performed. The presser members 4 are of duplicate construction and are provided at their rear ends with transversely-spaced ears 6, which are apertured to receive the rod 7, by means of which they are pivotally connected to lugs 8, pendent from the head 1 and grooved, as shown at 9, to receive the springs 5. The lugs 8 have openings to correspond with the openings of the ears 6 to receive the rod or pin 7 by means of which the parts 4 and 1 are pivotally connected. The presser members 4 are curved upward at their outer or front ends, as shown at 10, and engage with the cross-bar 11 of the frame 3. The springs 5 are approximately of U form and receive the pin or rod 7 in the bight or fold, the free ends of the members engaging with, respectively, the head 1 and the member 4, as shown most clearly in Fig. 3. Any suitable means may be provided to prevent displacement of the springs, and, as shown, the outer ends of the upper members are upturned to enter a depression 12 of the head 1, as indicated most clearly in Fig. 3.

The combined guide and stop-frame 3 is of U form, and its side members 13 have inner flanges 14 at their rear ends to overlap the terminal portions of the head 1 and receive the fastenings by means of which the frame is attached thereto. A companion bar 15 is spaced from the cross-bar 11 and is connected at its ends thereto, and the space formed between the two bars 11 and 15 is adapted to receive a tape, strip, or reinforcement when it is desired to stitch the same to the article being sewed.

When the parts are assembled, the presser members or elements 4 are in line, and by reason of their pivotal connection with the head 1 and the coöperation of an independent spring with each said members are adapted to yield to accommodate themselves to inequalities and differences of thickness in the goods being stitched, so as to exert a pressure thereon, which is essential to obviate skipping.

Having thus described the invention, what is claimed as new is—

1. In a presser-foot for sewing-machines,

- the combination of a head, a plurality of presser members pivoted to said head and adapted to have independent movement, a spring for each presser member, and a frame projected 5 from the head and having an upwardly and forwardly inclined cross-bar underlapping the outer ends of the presser members to form a stop therefor and normally hold the same in alinement, substantially as set forth.
- 10 2. In a presser-foot for sewing-machines, the combination of a head, a plurality of presser members pivoted to said head and adapted to have independent movement, a spring for each presser member, and a frame projected

from the head and having a cross-bar underlapping the outer ends of the presser members to form a stop therefor and normally hold the same in alinement and having a companion bar spaced from said cross-bar and connected at its ends therewith, substantially 15 as set forth.

In testimony whereof I affix my signature in presence of two witnesses.

JACOB R. HANN. [L. s.]
